RAYMOND R. WALKER, OF HOLLANSBEE, WEST VIRGINIA.

SHOCK-ABSORBER.

1,156,646.

Specification of Letters Patent. Patented Oct. 12, 1915.

Application filed March 8, 1915. Serial No. 12,721.

To all whom it may concern:

Be it known that I, RAYMOND R. WALKER, a citizen of the United States of America, and resident of Follansbee, county of Brooke, and State of West Virginia, have invented certain new and useful Improvements in Shock-Absorbers, of which the following is a specification.

This invention relates to shock absorbers, and more particularly to a shock absorbing device designed for application to motor vehicles.

The primary object of the invention is to provide an improved device of the air cushion type adapted for application to motor vehicles, whereby the shocks incident to road travel are effectually absorbed or reduced to a minimum.

A further object is to provide a device of the character mentioned which is double acting in that both the downward and return movements of its movable parts are so retarded as to cushion the shocks.

With these and other important objects in view, the invention resides in the features of construction, arrangement of parts and combinations of elements which will hereinafter be fully described, reference being had to the accompanying drawings, forming a part of this specification, in which—

Figure 1 is a central vertical section of the invention; Fig. 2 is a horizontal section taken on line 2—2, Fig. 1, showing means for adjusting the device with respect to the axle; Fig. 3 is a detail perspective view of the key constituting a part of the axle mounting; Fig. 4 is a view similar to Fig. 1, illustrating a modified structure; and Fig. 5 is a section on the line 5—5, Fig. 4.

Referring to said drawings, in which like designating characters distinguish like parts throughout the several views, 1 indicates a cylinder having a closed lower end 2 which may either be integral, as shown in Fig. 4, or in the form of a screw-cap, as shown in Fig. 1. Said cylinder is designed for connection, as by a ball and socket joint, designated generally by the numeral 3, to the axle of a vehicle, as will be more particularly explained hereinafter. Slidably disposed within the open upper end of said cyl-

inder 1 is a second cylinder 4 having suitable connection at its upper closed end with the vehicle frame (not shown) and having its lower end closed, as by a threaded plug 5; and operable within said second cylinder is a piston 6 having a vertically disposed rod 7 which extends centrally through the closed end 5 and has its lower end rigidly connected to the lower end 2 of cylinder 1. 60

An air chamber 8 is constituted between the lower end 2 of cylinder 1 and the lower end 5 of cylinder 4; a second air chamber 9 is constituted between the closed upper end of cylinder 4 and the piston 6, and a third air chamber 10 is constituted between said piston and the lower end 5 of cylinder 4. An inlet port 11 is provided for admitting air to the chamber 8, said port being controlled by a suitable check-valve, as a ball check 12. Communication between the chamber 8 and the chamber 10 is had through a port 13 in the lower end 5 of cylinder 4, a check valve, as 14, preventing return of air from chamber 10 to chamber 8. And communication is had between said chamber 10 and the chamber 9 through a port 15 provided in the piston rod 7 and leading through the piston 6, a check valve, as 16, preventing return of air from chamber 9 to chamber 10. An exhaust check valve 17 is provided at or adjacent to the upper end of cylinder 4 for controlling the passage of air from the chamber 9 through a port 18.

When the cylinders 1 and 4 are actuated to approach each other, the air in chamber 8 is compressed, being permitted to escape only through port 13 leading to chamber 10, said port being of such relatively restricted size that rapid passage of air therethrough is prevented. Simultaneously with the compression of air in chamber 8, the air in chamber 9 is compressed, being permitted to escape to the atmosphere but slowly through the port 17 which is of restricted size. The partial vacuum formed in chamber 10 is partially relieved by the air entering through port 13. Thus a double air cushion and a partial vacuum are afforded whereby the approach of said cylinders 1 and 4 is retarded for reducing downwardly directed shocks. Upon the re-

bound, or return upward movement, of cylinder 4, partial vacuums are created in chambers 8 and 9, and a cushion is formed by the air in chamber 10, said air being permitted to pass but slowly from chamber 10 to chamber 9 through restricted port 15. The suction created in chamber 8 acts to lift check-valve 12 for admitting air through the single inlet port 11 for replacing exhausted air.

It will be noted that the lower end of the port 15 opens into the chamber 10 at a considerable distance below the piston 6. The purpose of thus positioning said port 15 is to permit the closed end 5 of cylinder 4 to close the port on the rebound stroke, preventing the further escape of air from chamber 10, and thus to so confine the remaining air that actual engagement of the said end 5 with the piston is positively prevented. In like manner the port 17 opens into chamber 9 at a considerable distance from the closed upper end of cylinder 4 so that it will be closed by the piston near the end 25 of the down-stroke and a positive air cushion formed for preventing actual engagement between said piston and said closed upper end.

As is obvious, the exhaust port 17 and valve 16 may be dispensed with, if preferred, in which case the check valve 31 in port 15 is also dispensed with and an adjustable needle-valve 18 is provided for regulating the capacity of said port 15 for the passage of air, said needle-valve being directed through the piston rod 7 from the lower end of the latter and having its point located in or adjacent to said port whereby the latter may be restricted, as shown in Fig. 4. Thus, air alternately enters and exhausts from the chamber 9 through the port 15, said air shifting back and forth between said chamber 9 and said chamber 10 with the movements of said cylinder 4 with respect to the piston.

The socket portion of the ball-and-socket joint 3 may have a portion thereof, as 19^a, formed on or integral with the slide of the cylinder 1^a, as shown in Fig. 4, or may have said portion formed integral with the screw cap 2, as shown at 19 in Fig. 1. The ball 21 is formed on the end of a short stem 22 carried by an upright bar 23 which has its upper end received within a casing 24 which is formed on, or integral with, one side of a clamp 25 which embraces or seats upon an axle 26 of the vehicle.

Provision is made for adjusting my invention to vehicles varying in distance between the axle and the frame-mounting point, by forming a plurality of notches 27 in the side of the bar 23 adjacent to the axle, and providing a key or analogous device, as 28, shown in Figs. 1, 2 and 3, for interlocking

said bar with the clamp 25. Said key seats 65 in a recess 29 provided therefor in said clamp, has its outer face provided with teeth 30 for seating in said notches 27, and has its rear face shaped to correspond with the portion of the axle 26 to be engaged thereby. Having adjusted the bar 23 in the casing 24 to proper position, said key is inserted in the recess 29 in substantially the position shown in dotted lines in Fig. 1; then, applying the clamp to the axle, said key is driven forward, carrying its teeth 30 into the registering notches 27, as the clamp is tightened on the axle. Instead of the segment-shaped key 28, one or more substantially rectangular pins 28^a may be employed, as shown in Figs. 4 and 5, separate spaced recesses 29^a being provided therefor in the clamp.

What is claimed is—

1. A shock absorber comprising a pair of cylinders one of which is telescoped within the other, each cylinder having its outer end closed and the inner cylinder having its inner end closed, a piston disposed within said inner cylinder, a piston rod extending from said piston through the closed inner end of said inner cylinder and being fixed to the closed outer end of the outer cylinder, an inlet port for admitting air to the outer cylinder, a port for admitting air from said outer cylinder to the inner cylinder between the inner closed end of the latter and said piston, and a port leading through the piston and piston rod permitting communication between the portions of said inner cylinder at opposite sides of said piston, the last mentioned port opening at its lower end at a distance from the piston and being adapted to be closed by the inner closed end of said inner cylinder upon close approach of said end and said piston.

2. A shock absorber comprising a pair of cylinders one of which is telescoped within the other, each cylinder having its outer end closed and the inner cylinder having its inner end closed, a piston disposed within said inner cylinder, a piston rod extending from said piston through the closed inner end of said inner cylinder and being fixed to the closed outer end of the outer cylinder, an inlet port for admitting air to the outer cylinder, a check valve controlling said port, a port for admitting air from said outer cylinder to the inner cylinder between the inner closed end of the latter and said piston, a check valve controlling the last mentioned port, and a port leading through the piston and piston rod permitting communication between the portions of said inner cylinder at opposite sides of said piston, the last mentioned port opening at its lower end at a distance from the piston and being adapt-

ed to be closed by the inner closed end of said inner cylinder upon close approach of said end and said piston.

3. A shock absorber comprising a pair of 5 telescoped cylinders movable with respect to each other, said cylinders having their outer ends closed and the inner cylinder having its inner end closed to form a chamber at the outer end of said outer cylinder, a 10 piston dividing the inner cylinder into two chambers, means affording communication for air between said two chambers, except when said piston and said closed inner end closely approach each other, means permitting 15 the passage of air from the first mentioned chamber to the middle chamber, a check-valve controlled passage for admitting atmospheric air to said first mentioned chamber, and means maintaining said piston 20 in fixed relation to the outer cylinder.

4. A shock absorber comprising a pair of telescoped cylinders movable with respect to each other, said cylinders having their outer ends closed and the inner cylinder 25 having its inner end closed to form a chamber at the outer end of said outer cylinder, a piston dividing the inner cylinder into two chambers, means affording communication for air between said two chambers, except when said piston and said closed inner 30 end closely approach each other, a check-valve controlled passage for admitting air from the first mentioned chamber to the middle chamber, a check-valve controlled 35 passage for admitting atmospheric air to said first mentioned chamber, a port for exhausting air from the outer end of said inner cylinder, said port opening into said cylinder at a distance from its outer end 40 and being adapted to be closed by the piston when the latter closely approaches said end, and a piston rod attached to the closed outer end of the outer cylinder and extending through the closed inner end of the inner cylinder 45 whereby said piston is maintained in fixed relation to said outer cylinder.

5. A shock absorber comprising a pair of telescoped cylinders movable with respect to each other, said cylinders having their outer 50 ends closed and the inner cylinder having its inner end closed to form a chamber at the outer end of said outer cylinder, a piston dividing the inner cylinder into two chambers, means affording communication for 55 air between said two chambers, means permitting the passage of air from the first mentioned chamber to the middle chamber, a passage for admitting atmospheric air to said first mentioned chamber, a check valve 60 in said passage for preventing the escape of air from said first mentioned chamber when said cylinders move inward with respect to each other whereby an air cushion is formed in said chamber, and means maintaining

said piston in fixed relation to the outer cylinder, and adjustable means for connecting the outer cylinder to a vehicle axle. 65

6. A shock absorber comprising a pair of telescoped cylinders movable with respect to each other, said cylinders having their outer ends closed and the inner cylinder having its inner end closed to form a chamber at the outer end of said outer cylinder, a piston dividing the inner cylinder into two chambers, means affording communication for air between said two chambers, means permitting the passage of air from the first mentioned chamber to the middle chamber, a passage for admitting atmospheric air to said first mentioned chamber, a check valve in said passage for preventing the escape of air therethrough whereby a cushion is formed upon the approach of the outer end of the outer cylinder and the inner end of the inner cylinder, a check-valve controlled passage through which air 80 exhausts from the outer chamber of the inner cylinder, and means maintaining said piston in fixed relation to the outer cylinder. 85

7. A shock absorber comprising a pair of telescoped cylinders movable with respect to each other, said cylinders having their outer ends closed and the inner cylinder having its inner end closed to form a chamber at the outer end of said outer cylinder, a piston dividing the inner cylinder into two chambers, a passage permitting communication for air between said two chambers, said passage being adapted to be closed upon the close approach of the piston and closed end of the inner cylinder, a check-valve controlled passage for admitting air from the first mentioned chamber to the middle chamber, a check-valve controlled 95 passage for admitting atmospheric air to said first mentioned chamber, and a piston rod attached to the closed outer end of the outer cylinder and extending through the closed inner end of the inner cylinder whereby said piston is maintained in fixed relation to said outer cylinder. 100

8. A shock absorber comprising a pair of telescoped cylinders movable with respect to each other, said cylinders having their outer ends closed and the inner cylinder having its inner end closed to form a chamber at the outer end of said outer cylinder, a piston dividing the inner cylinder into two chambers, valve controlled means affording communication for air between said two chambers, a check-valve controlled passage for admitting air from the first mentioned chamber to the middle chamber, a passage for admitting atmospheric air to said first mentioned chamber, a check valve preventing the exhaust of air through said passage whereby a cushion of air is formed upon the approach of the outer end of the outer cylinder. 115 120 125

inder and the inner end of the inner cylinder, and a piston rod attached to the closed outer end of the outer cylinder and extending through the closed inner end of the inner cylinder whereby said piston is maintained in fixed relation to said outer cylinder.

In testimony whereof, I affix my signature in presence of two subscribing witnesses.
